UNITED STATES PATENT OFFICE.

GEORGE H. CRAMER, OF NORTH TONAWANDA, NEW YORK, ASSIGNOR TO HERSCHELL-
SPILLMAN CO., OF NORTH TONAWANDA, NEW YORK, A CORPORATION OF NEW YORK.

ELECTRIC-LIGHTING SYSTEM FOR CAROUSELS.

1,274,993.

Specification of Letters Patent.

Patented Aug. 6, 1918.

Application filed September 11, 1916. Serial No. 119,429.

To all whom it may concern:

Be it known that I, GEORGE H. CRAMER, a citizen of the United States, residing at North Tonawanda, in the county of Niagara 5 and State of New York, have invented new and useful Improvements in Electric-Lighting Systems for Carousels, of which the following is a specification.

This invention relates to the electric lighting system of carousels or merry-go-rounds and the like.

One of its objects is to provide a system of this character which is simple in construction and reliable in operation.

15 In machines which are set up and taken down daily, such as those traveling with circuses, carnival companies and the like, it is essential that the various parts of the machine shall be capable of ready assemblage 20 and dismemberment. With this in view, my invention has for the further object to so organize the lighting system that the electric connections can be quickly and conveniently made.

25 In the accompanying drawings: Figure 1 is a sectional top plan, partly diagrammatic view of a carousel embodying my invention. Fig. 2 is an enlarged fragmentary sectional side elevation thereof. Fig. 3 is an enlarged 30 fragmentary top plan view of the contact ring and associated parts. Fig. 4 is a cross section taken on line 4-4, Fig. 3. Fig. 5 is an enlarged sectional elevation of the contact ring and contact rollers. Fig. 6 is 35 a vertical longitudinal section of a sweep of the carousel showing the electrical circuit diagrammatically.

Similar characters of reference indicate 40 corresponding parts throughout the several views.

1 indicates the center pole or mast of the carousel on which is mounted the revolving hub 2 carrying the customary radial arms or sweeps 3. At the outer extremities of 45 said sweeps and suitably secured thereto are cornice sections 4, which preferably carry the lamps for illuminating the machine. The members 3 and 4 constitute the upper rotary frame of the machine. This frame 50 may be rotated by means of a pinion 5 mounted on an upright driving shaft 6 and meshing with an internal gear 7 secured to the underside of the sweeps 3.

Arranged below the hub 2 and concentric therewith are contact rings or members 8, 9, 55 spaced a suitable distance apart by means of the spacer blocks 10. Surrounding the outer edges of these contact members are bands 11 of copper or other suitable conductive material which are secured to said 60 rings by screws 12 or other appropriate means. These rings are secured to the revolving hub 2 by any desired means, but the construction shown in the drawings is suitable and consists of a plurality of radial 65 supporting arms 13, permanently fastened at their outer ends to the upper side of the contact member 8, while their inner ends are detachably secured to the underside of said hub by bolts 14. As shown in Fig. 1, each 70 of these supporting arms is preferably located in the intervening space between two adjacent sweeps, to facilitate the attachment and removal of the rings.

15 indicates fuse blocks preferably arranged upon the upper contact ring 8 and each located in the space between two adjacent sweeps to render their connections easily accessible. These fuse blocks may be of any well known construction, those 80 shown in the drawings being provided with sockets 16, fuse plugs 17 and two sets of positive and negative terminals or binding posts 18, 19 arranged at opposite sides of the blocks. The two wires 20 leading from 85 the corresponding positive and negative terminals 18 are electrically connected with the upper and lower contact rings 8 and 9 by securing their free ends to corresponding terminal plates 21 of copper or other suitable conductive material fastened to said rings. The two wires 22 leading from the corresponding positive and negative terminals 19 at the opposite side of each fuse block are connected to the corresponding terminals of a switch plug 23 adapted to be inserted in a metallic socket 24 preferably arranged in a recess in the lower inner end of the sweep 3, as shown in Fig. 6. Connected to this socket are positive and negative wires 100 or conductors 25 which pass upwardly through the sweep and may be seated in grooves in the top thereof. After passing along the sweep to a point short of its outer end, the wires extend downwardly through 105 it and are connected to the terminals of a

socket 26 carried by the sweep and similar to that at the inner end of the sweep. By extending the wiring along the top of the sweeps they are concealed from view and 5 present a more sightly structure.

A switch plug 27, similar to the plug 23, is adapted to be inserted in the socket 26. The terminals of the plug 27 are connected with the lead wires of a bank or series of 10 lamps 28 mounted on the sweep-frame of the machine. Such lamps are arranged in groups or banks on different sections of said frame and the circuit of each group includes such a fuse block and a pair of switch plugs 15 23, 27 and their coöperating sockets 24, 26.

Current is supplied to these lamp circuits from a battery or other source of supply by means of a pair of contact rollers 29 adapted to engage the upper and lower contact rings 8, 9. In the preferred construction shown each of these rollers is journaled in a bifurcated arm 30 pivoted by a horizontal pin 30^a to a horizontal rod 31 slideable lengthwise in openings in the walls of 25 a fixed casing or support 32. To obtain a good and reliable contact, these rollers are constantly pressed against the contact rings by springs 33 surrounding said rods and bearing at one end against the inside of the 30 casing while their other ends engage collars 34 secured to the rods. As shown in Fig. 2, the casing 32 is bolted to a shelf or platform 35, the inner end of which abuts against the stationary center pole 1 of the 35 machine, while its outer portion is carried by a brace 36. The current supply wires are fastened to binding posts 37 arranged at the outer ends of the rods 31, through which the current passes to the contact rollers.

40 After the machine has been set up ready for use, the lamp circuits are established by simply inserting the switch plugs 23 of the fuse blocks in the corresponding inner sockets 24 of the sweeps and inserting the 45 switch plugs 27 of the banks of lamps in the corresponding outer sockets 26 at the outer end of the sweeps. Each lamp circuit being thus completed, current will flow from the current source through one of the contact 50 rollers 29, companion contact ring 8, one side of the corresponding fuse block 15, one side of the switch plugs 23 and 27, the lamps and back through the other side of said plugs and said fuse block, through the 55 contact ring, and the companion roller to the current source. As shown in the drawings, these lamps are preferably connected

in series, although they may be connected in parallel, if desired.

In this improved lighting system the 60 electric connections for closing the circuits can be made quickly and conveniently and without going above the sweeps, as was necessary in the systems heretofore used, effecting a material saving of time which is 65 essential in machines of this character which in some cases are daily transported.

It is apparent that modifications in the constructions and arrangement of parts can be made without departing from the spirit 70 and scope of my invention, as covered by the appended claims.

I claim as my invention:

1. The combination of the rotary sweep-frame of a carousel, separate lamp-circuits 75 mounted on said frame, conductors forming a part of each lamp circuit and extending lengthwise of the sweeps of said frame, said conductors being connected at their ends to switch-sockets arranged at opposite 80 ends of the corresponding sweeps, contact rings rotatable with said sweep-frame, a switch plug for each lamp circuit having connections to said contact-rings respectively and adapted to engage one of said 85 sweep-sockets, a second switch-plug for each lamp-circuit connected with the leads thereof and adapted to engage the other of said sweep-sockets, and relatively stationary contact members engaging said contact 90 rings and adapted to be connected with a source of current.

2. The combination of the rotary sweep-frame of a carousel, separate lamp-circuits mounted on said frame, conductors forming 95 a part of each lamp-circuit and extending lengthwise of the sweeps of said frame, said conductors being connected at their ends to switch-sockets arranged at opposite ends of the corresponding sweeps, contact rings rotatable with said sweep-frame, a switch 100 plug, fuse blocks included in said circuits, respectively and mounted on one of said contact rings, each fuse block being electrically connected with said contact rings 105 and having a switch-plug adapted to engage the inner socket of the corresponding sweep, each of said lamp circuits including a switch plug adapted to engage the outer socket of the corresponding sweep, and relatively stationary contact-members engaging 110 said contact rings and adapted to be connected with a source of current.

GEORGE H. CRAMER.
